UNITED STATES PATENT OFFICE.

RICHARD A. KELLER, OF CHICAGO, ILLINOIS.

COMBINED RECEIPT AND ENVELOP.

1,168,004.

Specification of Letters Patent. Patented Jan. 11, 1916.

Application filed July 25, 1914. Serial No. 853,024.

To all whom it may concern:

Be it known that I, RICHARD A. KELLER, a resident of Chicago, in the county of Cook and State of Illinois, have invented certain 5 new and useful Improvements in Combined Receipts and Envelops, of which the following is a full, clear, and exact description.

The invention relates to combined receipts and envelops.

10 In delivering pay envelops, it is customary to require a receipt to be given for the contents of the envelop. The present practice is to make out or fill in the receipts and the envelops separately and to then distribute the receipts, and upon presentation of the receipts the envelops are delivered. In this practice, errors sometimes occur in making out envelops from the entries on the receipts or vice versa and furthermore considerable time is consumed in separately filling in the necessary identifying memoranda 20 on the envelop and the receipt.

One object of the invention is to provide a combined receipt and envelop by which 25 the writing on the receipt will be reproduced on the envelop by means of a sheet of carbon and thereby the work of separately filling in the identifying data on the envelop and corresponding data on the receipt will be avoided. Absolute accuracy is attained so that 30 the identifying data on the envelop and receipt will, at all times, correspond.

A further object of the invention is to provide an improved combined envelop and receipt.

The invention consists in the several novel features hereinafter set forth and more particularly defined by claims at the conclusion hereof.

40 In the drawings: Figure 1 is a perspective of a combined envelop and receipt embodying the invention. Fig. 2 is a view, showing the receipt and envelop in extended position and before being folded for use. Fig. 3 is a view of the opposite face of the same. Fig. 4 is a section showing the device 45 folded and in position assumed when the receipt and envelop are being filled in.

The device is formed of a single piece of 50 paper at one end of which an envelop 6 is formed by folding a portion 7 of the paper and flaps 8 over a portion of the sheet and securing them in the usual manner to form the envelop 6. A flap 9 for closing the envelop is formed by a portion of the sheet of

paper and is gummed as at 10, so that when the sheet is severed on a line of perforations 11, the flap 9 may be folded over the portion 7 of the envelop and secured thereon to seal the envelop and its contents. A portion of 60 the sheet forms a receipt slip or ticket which has printed thereon a form for a receipt as indicated at 14 and has a line or space 15 for an identifying character, a line or space 16 for the name of the person to whom the 65 envelop is to be delivered, a line or space 16^a for the amount of wages and a line or place 17 for the signature of the person in acknowledgment of the receipt of the envelop and its contents.

70 The invention is shown as particularly adapted for pay envelops and receipts and the receipt-form 14 is printed thereon together with a space 18 for indicating the date for which the wages are being paid, 75 and also a table indicating the time for labor for which payment is being made. The face of the envelop has a line 20 corresponding to a line or space 15 on the receipt, a line or space 21 corresponding to the line 16 of the receipt and a line or space 22 corresponding to the line or space 16^a on the receipt. When the receipt is folded on the line of perforations 11 over the face of the envelop 6, the spaces or lines 15, 16 and 16^a will register 80 with and overlie the lines or spaces 20, 21 and 22 on the envelop so that if a sheet of carbon is interposed between the sheet and the envelop, the identifying number, name and amount when written on the receipt will 85 be reproduced on the envelop. After the envelop and receipt have thus been filled in, the receipt is severed from the closing flap of the envelop on the line of perforations 11, at which point the sheet is perforated. The 90 receipts are then delivered to the workmen and the correct amount, corresponding to the entry on the receipt and envelop is placed in the envelop and then the latter is sealed. Upon presentation of the receipt 95 with signature thereon, the cashier delivers the envelop 6, having the corresponding number, name and amount written thereon and containing pay of the person identified and in the amount indicated on the receipt and envelop, to the presentor of the receipt. If desired, the date of presentation of the 100 receipt and payment may be stamped on the place indicated at 27.

The invention thus exemplifies a combined 110

envelop and receipt constructed so that an impression of the receipt may be made upon one face of the envelop corresponding to the identifying and other data placed on the receipt, whereby errors, such as result from placing the data separately on the envelop and the receipt, are entirely avoided. The time consumed is materially lessened in this work, and, in places where many employees 10 must be paid, there is a very material saving in time as well as saving in trouble resulting from errors which sometimes occur.

The combined envelop and receipt is 15 formed of a single piece of paper, so that it may be produced at a low cost.

The invention is not to be understood as restricted to the details set forth, since these may be modified within the scope of the appended claims without departing from the spirit and scope of the invention.

Having thus described my invention, what I claim as new, and desire to secure by Letters Patent, is:—

25 1. The combination of an envelop, having a closing flap at one side, of a severable slip extending from the free edge of said flap and foldable over one face of the envelop while said flap is open, so that an impression 30 of the matter written on said slip may be made on the envelop upon the interposition of a reproducing element, the face of the envelop receiving the impression and the outer face of the slip having printed thereon simi-

lar identifying data disposed to register 35 when the slip is folded over the envelop.

2. The combination with an envelop having a closing flap at one side, of a slip extending from the free edge of said flap and foldable over one face of the envelop while 40 said flap is open, so that an impression of the matter written on the slip may be made on the envelop upon the interposition of a reproducing element, the face of the envelop receiving the impression and the other face 45 of said slip having printed thereon similar identifying data disposed to register when the slip is folded over the envelop, a line of perforations being formed between the slip and the flap of the envelop. 50

3. The combination with an envelop, having a closing flap at one side, of a severable slip extending from the free edge of said flap and foldable over one face of the envelop while said flap is open, so that an impression of the matter written on the slip may be made on the envelop upon the interposition of a reproducing element, the face of the envelop receiving the impression and the outer face of the slip having printed 55 thereon identifying data disposed to register when the slip is folded over the envelop, the flap having a gummed margin adjacent the slip. 60
